(57) **CLAIM**

The ornamental design for a connector, as shown and described.

DESCRIPTION

FIG. 1 is a perspective view of the connector of my design with a mating connector and rope shown in phantom;

FIG. 2 is a side elevational view thereof, the opposite side being a mirror image thereof;

FIG. 3 is a top plan view thereof;

FIG. 4 is a bottom plan view thereof; and,

FIG. 5 is an end view thereof, the opposite end view being a mirror image thereof.

The broken lines are for illustrative purposes only and form no part of the claimed design.
